UNITED STATES PATENT OFFICE.

CHARLES H. LUSH, OF FREEPORT, NEW YORK, ASSIGNOR TO BEACON MFG. & SALES CO., INC., OF FREEPORT, NEW YORK, A CORPORATION OF NEW YORK.

SIGN HOLDER.

Application filed October 3, 1923. Serial No. 666,382.

To all whom it may concern:

Be it known that I, CHARLES H. LUSH, a citizen of the United States, and a resident of Freeport, in the county of Nassau and State of New York, have invented a new and Improved Sign Holder, of which the following is a full, clear, and exact description.

This invention relates to sign holders and has for an object to provide an improved construction which will produce a pleasing appearance and at the same time present a maximum strength.

Another object of the invention is to provide a sign holder wherein the sign plates may be quickly and easily removed and replaced.

A still further object, more specifically, is to provide a sign holder in which a pair of telescoping frames are used and mounted in such a manner as to be readily disconnected when the sign is to be packed for shipment.

In the accompanying drawing—

Figure 1 is a perspective view of a sign, disclosing an embodiment of the invention.

Figure 2 is a vertical sectional view through Figure 1, approximately on line 2—2.

Figure 3 is a fragmentary sectional view on an enlarged scale through Figure 1 on line 3—3.

Figure 4 is an enlarged fragmentary sectional view through Figure 1, approximately on line 4—4.

Figure 5 is a sectional view similar to Figure 3 but showing a slightly modified construction.

Referring to the accompanying drawing by numerals, 1 and 2 indicate supporting standards which are substantially A-shaped with flat sections 3 forming feet and flat top sections 4 forming bases for receiving the angle base plates 5 and 6. The angle base plates 5 and 6 are each preferably formed from a substantially diamond-shaped piece of metal bent centrally for forming a vertically extending triangular-shaped portion and a horizontally extending triangular-shaped portion. The horizontal triangular-shaped portions of the plates 5 and 6 are each provided with apertures for receiving suitable bolts 8 whereby the outer frame 9 is secured rigidly to the base plates 5 and 6. These base plates are riveted or otherwise rigidly

secured to the base sections 4 of the respective standards 1 and 2.

Any desired number of bolts 10 are also fitted into the vertical portions of the plates 5 and 6, said bolts extending through one flange of the frame 9 whereby the frame is held at its bottom and sides near the bottom. By using bolts, the frame 9 may be disconnected at any time. If preferred, rivets might be used or some other fastening means.

The frame 9 is L-shape in cross section at any point as clearly indicated in Figure 3. Co-acting with the frame 9 is an inner clamping frame 11 which is preferably rectangular in cross section as indicated in Figure 3 but slightly smaller than the frame 9 whereby it may be nested in frame 9 and clamp one or more plates 12 in place. As shown in the drawing, there are two plates 12 designed to receive suitable information but if preferred, one plate could be used or

more than two, without departing from the spirit of the invention. It will be noted that the frame 11 fits snugly against the base flange 16 and presses the plates 12 against the base flange 16 and whereby a neat and strong structure is produced. The frame 9 is provided with suitable apertures at the top whereby bolts, pins or other fastening means 17 may be positioned therein for locking the frames together at their tops while

the lugs 7 pressed up from the frame 9 hold the frames together at the bottom. It will thus be seen that by the construction set forth it is only necessary to remove the bolt 17 in order to remove the frame 11 from frame 9. It will be understood that the frame 11 is sufficiently loose fitting in the frame 9 to permit frame 11 to be easily moved inwardly and outwardly while at the same time presenting a fairly snug fit.

In Figure 5 will be seen a modified form of the invention in which the construction is identical with the other forms of the invention except that the frame 11' is formed from angle iron instead of a flat piece as shown in the preferred form. When the angle iron is used, the outward extending flange 15 is provided with apertures for receiving the respective bolts 17. This presents a very strong and neat appearance.

What I claim is:

1. A sign holder, comprising a pair of standards having horizontal base portions, a

base plate rigidly secured to each base portion, each of said plates having a horizontal section and a vertical section, an outer frame element of substantially an L-shape in cross section formed with pressed up lugs at the bottom, means for removably securing said frame to said base plates, said securing means connecting the frame to the base plates on their horizontal portions and vertical portions, an inner frame element disposed within the outer element, and removable fastening elements at the top of the frame co-acting with said lugs for locking said inner frame element to the other frame element.

2. A sign holder, comprising an outer frame member of substantially an L-shape in cross section, an inner frame substantially rectangular in cross section fitting flatwise, 20 against the base flange and said outer frame, said outer frame having stops projecting upwardly from its lower horizontal section, re-

movable bolts extending from its upper horizontal section co-acting with said stops for locking said inner frame in place, and a pair of supporting members including a pair of substantially A-shaped legs removably connected with said outer frame member. 25

3. A sign holder, comprising an outer frame element adapted to receive a sign plate, 30 an inner frame element fitting into the outer frame element and clamping said plate in said outer frame element, means for holding said inner frame element in operative position, an angle plate having a horizontal and a vertical section removably secured to each of the lower corners of said outer frame element, the vertical section being secured to the sides of said frame while the horizontal section is secured to the base of said frame, 40 and a substantially A-shaped supporting standard secured to each of said angle plates. 45

CHARLES H. LUSH.
